UNITED STATES PATENT OFFICE.

GLADSTONE FISH, OF FALL RIVER, MASSACHUSETTS.

HEAD MECHANISM FOR OPERATING HEDDLES IN PLAIN LOOMS.

Application filed November 3, 1923. Serial No. 672,556.

To all whom it may concern:

Be it known that I, GLADSTONE FISH, a citizen of the United States of America, residing at Fall River, in the county of Bristol, State of Massachusetts, have invented certain new and useful Head Mechanism for Operating Heddles in Plain Looms, of which the following is a specification, reference being had therein to the accompanying drawings.

The principal object of my invention is to produce a simple, positively operated mechanism, that can, when desired, be easily, quickly and cheaply substituted for the cam-mechanism operating the heddles of a plain-loom; the result being a loom that can weave plain cotton cloth or, for example, a marquisette, i. e. a leno-weave completed in two picks.

It is well known that marquisette fabric is commonly manufactured upon dobby-looms, and that it cannot be made upon a plain-loom; though there are various loom makers who have special appliances which may be incorporated in their respective looms for the purpose of making leno-weaves.

It is also well known that the dobby-head is expensive in cost, and is complicated in structure, and cannot be substituted for the cam-operating harness mechanism of a plain-loom, without modifications and great expense, and without changing the structure of the plain-loom itself to such an extent that much time and cost is involved. The particular reason why the dobby-head is objectionable is that its mechanism can have no less than eight bars on the barrel of the chain cylinder to carry the pattern chain, and that means apparatus capable of weaving a 16-pick weave, and, if used to weave marquisette, it means the use of complicated mechanism, having capacity for great variety of weaves, absolutely not needed in a two-pick leno-weave.

Still further, as the dobby has a non-positive motion, it frequently mispicks.

Now by means of my invention, I provide simple apparatus that may be incorporated in a plain-loom without much change in the loom, to operate successfully in the production of, say, marquisette, and I do so by eliminating the various parts of the dobby-head between the main lever of the dobby and the harnesses, and substituting therefor the various features of my

invention, whereby may be successfully operated the number of heddles required in a plain-weave, or in a leno-weave requiring only two picks to complete the weave.

In the drawings illustrating the principle of my invention and the best structure now known to me embodying the same,

Fig. 1 is an elevation of my invention as applied to a plain-loom; the picking mechanism, lay, loom-beam, heddles of the harnesses, the warp-threads, and the cams and treadles, no longer operating the harnesses, being omitted for the sake of clearness;

Figs. 2 and 3 show in end elevation and in plan, respectively, what appears in Fig. 1; Fig. 2, however, also showing the doup-heddles omitted from Fig. 1.

Fig. 4 is an enlarged detail of the harnesses and heddles, showing in cross section one pair of doup-harnesses with their lifting heddles and doup-heddles, and doup and ground warp-ends in open shed formation; the rear lifting heddle and doup-heddle being raised, and ground heddle lowered; also broken off section of open shed, and marquisette.

Fig. 5 indicates the position assumed by the doup and ground ends, when the shed is closed; while

Fig. 6 shows the shed formed by the doup-end and the ground-end, when the front lifting heddle and doup-heddle are raised and the doup-heddle is lowered to form the next open shed with the doup-end on the side of the ground warp end opposite to that shown in Fig. 4; also a broken-off section of open shed and marquisette.

Fig. 7 is an exaggerated, very much enlarged section of marquisette, to make plain its weave.

A plain-loom frame 1, Fig. 1, has mounted thereon, the usual crank-shaft 2 and cam-shaft 3, the former driving the latter through gears 4, 5, the gear 4 being, in diameter, one-half that of gear 5.

A T-rock lever 6 is pivoted at its crossing, to the frame 1, while the free end portion of the cam-shaft 3 is provided with a crank 8, which, by means of a pump rod 9, is connected to the free end portion of the trunk 10, of the T lever. The top arm 11 and the bottom arm 12 of the T lever each have a short bar 13, 14, projecting sideways therefrom, and over these are bent various heavy steel wires 15, 16, 17, 18, 19, 20, Figs. 1 and 3, which, in turn, are hooked into

various leather straps 21, 22, 23, 24, 25, 26, 27, 28, 29, 30, 31, 32 passing over their respective sheaves 33, 34, 35, 36, 37, 38, 39, 40, 41, 42, 43, 44, mounted upon the loom arch, 5 and connecting with their respective harnesses 45, 46, 47, 48, 49, 50, Fig. 2.

From front to back, see Figs. 2, 3 and 4, there are the two pair of doup-lifting harnesses 45, 46, and 47, 48; and two selvage 10 harnesses 49, 50; and one ground harness 51; the latter being operated by a jumper-mechanism later to be described.

The first and third doup-lifting harnesses 45 and 47; and the first selvage harness 49 are 15 connected to their respective stacks and hooked wires, to the short bar 14 on the bottom arm 12 of the T-rock lever; while the second and the fourth doup-lifting harnesses and second selvage harness 50 are 20 connected through their respective straps and hooked wires, to the short bar 13 on the top arm 11 of the T-rock lever. Each of these harnesses together with the ground harness, has a spring connection with the 25 floor.

Each pair of doup harnesses, as 45 and 46, Figs. 2 and 4, has doup lifting heddles 70, 71, in each harness, connected together by U-shaped doup heddles 72, that, like the 30 harnesses, are connected through their frames 73, 74, and springs to the floor. A reference to Figs. 4, 5 and 6 will make their construction plain. Each doup end 75 passes through an eye 76 in the doup-hedde 35 72 and between the lifting heddles 70, 71, while the ground end 77 of the warp simply passes between the lifting heddles after having passed through its heddle in the ground harness 51.

40 I will now describe how the harnesses operated as above described, cause the lifting doup-heddles, doup-heddles and ground heddles to cross-weave the doup and the ground ends and make marquisette.

45 Starting, for example, with the lifting heddles 73, 74, and doup heddle 72, as shown in Fig. 5, the shed being closed, the rear lifting harness 46, and its heddle 70, Fig. 4, are raised in the manner just explained, the 50 doup-heddle with doup-end 75 passing up by the "near" side of the descending ground end 77 controlled by the ground harness 51, and weaving, after pick filling 78, what is 55 shown in Fig. 4 and Fig. 7, at *x*. After the pick filling 78, the lifting heddle 70 and the doup-heddle 72 and ground heddle return to the position of closed shed, as in Fig. 5, Fig. 7, at *y*. Next, the front lifting harness 45 and heddle 71, and doup-heddle 60 72 being lifted at *z*, Fig. 7 on the "off" side of the ground end 77, which descends as shown in Figs. 6 and 7; and putting in a twist *y*, form a new shed. The next pick 79 following, the above described crossings 65 are repeated; the doup-end 75 always being

on top of the shed, and the ground warp end 77, on the bottom; with a whole twist in the warp ends in one direction, and then a whole twist in the opposite direction, after each filling pick; a marquisette or leno-weave resulting.

I will now describe the jumper, and the slackener apparatus which are employed in making marquisette, for example. A jump-rock-shaft 52, supported on the arch of the frame, has a pair of arms 53, 54, which are connected by iron rods to the top of the ground harness 51. To impart motion to the rock-shaft, there is a crank 57 and the crank-shaft 2, an arm 58 on the jump-rock-shaft 52, and a jump rod 59 connecting said crank 57 and said arm 58.

The slackener apparatus comprises a doup-end rod 60, Figs. 2 and 3, pivotally supported near its end-portion, by a pair 85 of links 61, 62, which in turn are pivoted to portion 63 of the loom frame, while an arm 64 fixed to the doup-end rod is connected to an operating rock-arm 65 on the jump-rock-shaft 52, by a link 66, rigidly 90 connected to arm 64.

It is here to be particularly noted, in the adaptation of the jumper end the slackener of a dobby-loom to a plain-loom, that the doup-end rod and the ground harness have operative connections that are rigid rather than flexible, as iron links rather than leather straps; and that the slackener is operated by the crank-shaft rather than by the cam-shaft; the substitution of a rigid 100 for a strap connection for the ground harness, and for the doup-end-rod, being the second feature of my invention; while the third feature may be said to reside in operating the slackener through the crank-shaft, 105 rather than the cam-shaft, as is ordinarily done in a dobby-loom.

From the above description, and from the assumptions previously made, as to omitted 110 elements of the loom, it will be understood that the loom is ready for operation to weave marquisette.

The loom is started. The crank-shaft 2, Figs. 2 and 3, revolves once in each half revolution of the cam-shaft 3, by reason of the gears 4 and 5, that is, the proper shed is formed for each pick by each half revolution of the cam-shaft and by each complete revolution of the crank-shaft; that is to say, one-half revolution of the cam-shaft 115 3 causes the pump-rod 9 and the T-rock-lever to move in one direction, so that, for example, the first and third doup lifting harness 45 and 47, and the first selvage harness 49, connected to the lower arm 14 of the T-rock-lever, through the hooked wire rods, and leather straps passing over their respective streams, are drawn down by their weight and the springs to form the closed 120 shed, Fig. 5; while the second and fourth 125 harnesses 46 and 50, connected to the upper arm 13 of the T-rock-lever, through the hooked wire rods, and leather straps passing over their respective streams, are drawn down by their weight and the springs to form the closed 130 shed, Fig. 5;

doup harness 46 and 48 and the second selvage harness 50, connected to the top arm 13 of said lever through the hooked wire rods and leather straps passing over their 5 respective sheaves, are raised from closed shed to their top position or open shed; and upon the next half revolution of the cam-shaft 3 the T-rock-lever moves in an opposite direction, causing the doup lifting harnesses to reverse their movements, and vice 10 versa, for each succeeding half revolution.

But while these doup lifting harnesses are thus operating from bottom or closed shed to top or open shed, or vice versa, the ground 15 harness 51 is raised and lowered through the action of the crank-shaft 2, revolving twice as fast as the cam-shaft 3; each revolution of the crank-shaft causing the jump-rod 59 to oscillate the jump-rock-shaft 52 20 and the arms 53 and 54, and the iron rods 55 and 56 supporting the ground harness 51; so that the ground harness rises and falls to open shed and closed shed positions, during each up and each down movement 25 of the doup lifting harnesses, and the selvage harnesses. But each vibration of the jump-rock-shaft moves the rock-arm 65, link 66 and doup-end arm 64 and rod 60, pivotally supported by the 30 links 61 and 62, pivoted to the frame 63, thereby causing no strain upon the doup-ends, due to their crossings of the ground ends brought about by the doup lifting harnesses.

35 In fine, the above-described apparatus will weave a marquisette, by interlacing the doup and the ground ends of the warp, previous to each pick, and, at the same time, operating mechanism, to give a bit of slack to 40 the doup ends as they are raised by the doup harnesses.

That this plain-loom, provided with my invention, may weave a plain-weave, obviously all that is required is that the jumper 45 and the slackener mechanism, together with the ground harness, shall be disconnected from the crank-shaft; and proper harnesses substituted for the doup and selvage harnesses, and connected to the T-rock-lever 50 by properly selected wires and straps.

In conclusion, the above-described apparatus embodying my invention, is simple in structure, and small in cost of manufacture; is positive in its motions, and enables a 55 plain-loom to weave a plain-weave or a leno-weave requiring only two picks.

Desiring to protect my invention in the broadest manner legally possible.

What I claim is:

60 1. In a plain-loom, a cam-shaft; a crank

on said cam-shaft; a T-rock-lever; a pump-rod connecting the trunk of the T-lever and the crank on the cam-shaft; harnesses, including a ground harness; sheaves; wires and straps, supported by their respective 65 sheaves, connecting the top arm and the bottom arm of the T-lever, with its respective harnesses; a jumper mechanism comprising a jump-rock-shaft; a pair of rock-arms on said rock-shaft; a rod connecting each of 70 said rock-arms to said ground-harness; a slackener mechanism comprising a doup-end rod; a link at each end of said doup-end rod, pivoted to said rod and to said frame; an operating arm fixed to said jump-rock- 75 shaft; an arm on said doup-end-rod; a link to connect said arms; a crank-shaft operatively connected to the cam-shaft; a crank on said crank-shaft; a driving arm on said jump-rock-shaft; and a jump-rod connect- 80 ing said crank on said crank-shaft and said driving arm on said jump-rock-shaft; all designed to weave leno-weaves that may be completed in two picks.

2. In a plain-loom, jumper mechanism 85 comprising a jump-rock-shaft; a pair of rock-arms on said jump-rock-shaft; a ground harness; a rigid rod connecting each of said jump-rock-arms to said ground-harness; a slackener mechanism comprising 90 a doup-end-rod; a link at each end of said doup-end-rod, pivoted to said rod and to the frame of the loom; an operating arm fixed to said jump-rock-shaft; an arm on said doup-end-rod; a link to connect said 95 arms; a crank-shaft operatively connected to the cam-shaft; a crank on said crank-shaft; a driving-arm on said jump-rock-shaft; and a jump-rod connecting said crank on said crank-shaft and said driving arm on said 100 jump-rock-shaft; all designed for use in weaving leno-weaves that may be completed in two picks.

3. In a plain-loom, a slackener comprising 105 a rock-shaft; an arm on said shaft; a doup-end-rod; a link at each end of said doup-end-rod pivoted to said rod and to the frame of the loom; an arm fixed to said doup-end-rod; a link connecting the free end of said arm and the arm on said rock-shaft; a crank-shaft; an arm on said shaft; an arm on said rock-shaft; and a driving rod to connect said two latter arms; all designed to give positive vibrations to the doup-end-rod, when embodied in a plain-loom, for 110 weaving leno-weaves that may be completed in two picks.

In testimony whereof I hereunto affix my signature.

GLADSTONE FISH.
